JOURNAL BOX STRUCTURE FOR RAILWAY VEHICLES

Albin K. Strandberg, Norvelt, Pa., assignor to
American Locomotive Company, New York,
N. Y., a corporation of New York

Application February 20, 1947, Serial No. 729,868

11 Claims. (Cl. 308—47)

1

This invention relates to journal box structures for railway vehicles, and more particularly to an articulated closure lid structure therefor.

The invention has particular reference to an improved closure lid structure of the character specified wherein a resilient member normally receiving closure pressure at its axial center is arranged centrally of a lid for transmission of the closure pressure to the outer face of the lid in regions adjacent the marginal edges of the journal box access opening.

More specifically, the invention has reference to an improved closure lid structure wherein the lid is provided with a large central pocket opening outwardly, and a large spring disc, such as a "Belleville" type spring disc, is yieldably secured to the center of the lid concentric with the pocket whereby only the marginal portion of the disc is in contact with the lid, the depending end of a pivoted lid-supporting hood being attached centrally of the spring disc so that pressure is brought to bear thereon under the influence of a closure spring, co-operatively associated with the hood and journal box, and such pressure is transmitted by the spring disc to the closure lid at points thereon in close proximity to the marginal edges of the access opening of the box.

When railway truck wheels ride over regularly spaced rail joints, regular shocks or upward accelerations occur which are transmitted by the journal box to the lid assembly, especially, in the case of conventional lid assemblies, to the hood and main pressure spring parts, and the inertia forces developed by these accelerations will cause the lid to vibrate and pound on the surfaces surrounding the journal box access opening.

These pounding vibrations are harmful and should be subdued or prevented because they cause local wear along the surface of the box about the access opening, wear of the hood eyes upon the hinge pintle, wear at all points of contact of the main pressure spring, and wear on the spring roller and lug cam face of the journal box.

The undamped vibration and wear causes a loosening of the lid of conventional structure and a reduction of the closing spring pressure, thereby permitting the lid to flap slightly open with the vibration, and let dust, dirt, cinders, foreign material and moisture enter the box and come in contact with the journal and its bearing.

The principal object of the present invention is to provide a journal box structure which is free of the above mentioned defects.

Another object is to provide an improved journal box closure lid structure wherein the usual concentrated pressure area substantially centrally of the lid is eliminated.

Another object is to provide an improved closure lid structure which includes a vibration and

shock-absorbing element as an integral part thereof.

A further object is to provide an improved closure lid structure which will remain firmly seated on its journal box face with a substantially constant and uniform pressure regardless of vibration and shock occasioned by the passing of the truck wheels over regularly spaced rail joints or other irregularities.

10 A further object of the invention is to provide an improved closure lid structure which substantially will not vibrate and pound on the face of the journal box, whereby entry of foreign matter and wear between the contacting surfaces and the hinge elements is prevented.

15 Another object is to provide an improved closure lid structure whereby a constant and uniformly distributed pressure contact between the closure lid and the face of the journal box is obtained, regardless of any inaccuracies in the alignment of the hinged connection therebetween.

20 A further object is to provide an improved closure lid structure which, by reason of its freedom from vibration and shock, permits the efficient use of a gasket between the closure lid and the journal box face when desirable or necessary.

25 Other and further objects of the invention will appear from the following description, the accompanying drawings and the appended claims.

30 Referring to the drawings forming a part of this application:

Figure 1 is a front elevation of the improved closure lid structure;

35 Fig. 2 is a fragmentary detail view in section of the hood and associated parts with the spring disc undeflected;

Fig. 3 is an enlarged fragmentary transverse sectional view taken on the line III—III of Fig. 1;

40 Fig. 4 is an enlarged vertical sectional view taken on the line IV—IV of Fig. 1, the journal box and hinge pin being shown diagrammatically;

Fig. 5 is a foreshortened enlarged side view of the structure shown in Fig. 1; and

45 Fig. 6 is a side view of a lid structure constructed in accordance with a modification of this invention.

Referring to the drawings in detail and to Fig. 4 in particular, a portion of a conventional journal box, shown diagrammatically, is indicated at 10. It has an access opening 11 therein and is provided with an upstanding hinge lug 12 integral with and centrally of its upper horizontal surface.

50 The hinge lug is of cam-like configuration having angularly related cam surfaces 13 and 14, and has a transverse bore 15 extending through the lug in which is disposed a hinge pin 16.

A closure lid structure is connected to the journal box by the hinge pin 16. The closure lid struc-

ture includes a lid 17 for closing the access opening 11, a hood 18 for supporting the lid 17, a spring 19 between the hood and lid, and connecting means, indicated generally by the reference numeral 20, for articulating the hood and lid.

The hood 18 is provided at its top with eyes 21, at an intermediate point with a transverse cylindrical spring seat 22 and at its lower end portion with a ball or semi-spherical knob 23. Two transversely spaced holes 24 are provided between the seat 22 and knob 23. The knob 23 is disposed at the center of the access opening 11 and has a central or axial orifice 25. A strengthening flange 26 surrounds the knob 23 and blends into the remainder of the hood.

In the drawings a pressed steel hood-lid construction is shown, by way of example. All parts of the connecting means 20 are first secured to the hood, forming a unit for attachment to the lid. In accordance with the present invention, the connecting means 20 includes a flat annular plate 27, provided with a large central aperture 28 and diametrically opposite radial projections or ears 29 integral therewith. A spring disc 30 of a diameter slightly smaller than plate 27, and provided with a central aperture 31 slightly smaller than the aperture 28, is disposed in concentric facing relation with the plate 27 on the semi-spherical knob 23, with the disc 30 inwardly of the plate 27. They are retained on the knob 23 by a relatively small dished washer 32 secured to the knob 23 by a rivet 33 passing through the washer 32 and the orifice 25 of the knob 23. The disc 30 and plate 27 are loosely secured on the knob by the washer in the clearance space 34 provided by the diverging opposite faces of the knob and washer. The spring disc 30 is shown, by way of example, as a Belleville spring disc, which is normally conical in its undeflected state, as shown in Fig. 2, but which flattens under deflection, as shown in Figs. 3 and 4.

Furthermore, as clearly shown in Figs. 2 and 4, the central aperture 28 in the aforesaid plate 27 is of a size, in relation to the semi-spherical knob 23, to provide substantial clearance therebetween. However, the central aperture 31 in the spring disc 30 is of such size as to permit only partial entry therein of the knob 23 whereby the closure force normally exerted by the hood 18, in response to the spring 19, is applied to the spring disc 30 axially thereof, as will later be described, while at the same time permitting limited universal movement of the spring disc 30 on the convex surface of the knob 23 relative to the hood 18.

Further, in accordance with the present invention, the closure lid 17 is provided centrally thereof with an outwardly facing frusto-conical pocket 35 terminating in a shouldered annular plane surface providing a seat 36 for the spring disc 30. Seat 36 is inwardly of the outer face of the lid 17 so that the spring disc 30 is housed in the pocket 35 and so that the plate 27 can be flush on the lid outer face. The lid is connected to the aforesaid semi-spherical knob 23 of the hood 18 by the attachment of the annular plate 27 to the lid by means of rivets 37 in the ears 29 whereby the spring disc 30, also carried by the knob 23, is initially compressed with its marginal portion seated on the seat 36.

As thus attached, the closure lid 17 is free for limited articulation, with the attached annular plate 27 and spring disc 30 as a unit, relative to the supporting hood 18 and the journal box 10, with the spring disc 30 sufficiently free to normally flex relative to the plate 27 and the lid 17 whereby

5 vibrational forces transmitted to the closure lid from the vehicle truck are substantially damped.

The closure lid 17 is further provided with a linear rib 38, which extends parallel with, adjacent to and about the margins of the lid on the inner face thereof to impart rigidity thereto, and serving to deflect a lubricant from the contacting surfaces of the journal box 10 and lid 17.

10 As clearly shown in Figs. 3 and 4, the marginal edge portions of the closure lid 17 are turned substantially at right angles thereto whereby, when the lid 17 is in normal closed position, the turned marginal flanges 39 overlap the outer margins defining the journal box 10, in slightly 15 spaced relation thereto so that water and dirt are excluded from passage at the juncture between the journal box face and the inner face of the closure lid.

15 The uppermost flange 39 of the closure lid 17 has its intermediate portion cut away and the remaining spaced ends, thus formed, are sheared from the lid proper for a short distance therealong and bent upwardly at right angles to provide a pair of suitably spaced, upstanding tabs 25 40. The upper hinged end portion of the supporting hood 18 is received freely between the tabs 40 and substantial rotary movement of the closure lid 17 relative to the hood 18 and the journal box 10 is prevented.

20 The lowermost flange 39 of the closure lid includes an intermediate reversely bent portion forming a depending finger piece or tab 41 which may be manually grasped for opening and closing the lid 17. If desired, tab 41 may be eliminated, as shown in the modification of Fig. 6, and the hood provided with a depending lever 41a, so that all forces required to open and close the lid structure will be applied to the hood only.

25 The spring 19 is shown, by way of example, as a double torsion spring having coils 42 disposed on the seat 22, a loop 43 engaging, through a roller 44, the cam lug 12, and depending legs 45 extending through the holes 24 and exerting their force on the hood at the inner periphery of these holes. The ends of the legs 45 are bent slightly to aid in securing them in the holes 24. As can be seen from Fig. 1, the spring is wound to provide a wide loop 43 for a long roller 44. This reduces the amount of roller pressure and wear on the cam face 13.

30 The pressure of the spring 19 is transmitted to the lid 17 by means of the knob 23 pressing against the center of the spring disc 30, the spring disc 30 pressing at its peripheral margin against the lid seat 36 and forcing the lid tightly against the box face.

35 The lid structure is shown in operative position in Fig. 4. It has been shown vertically but actually the box face is slightly inclined. The lid 55 may engage the solid metal face 46 of the box surrounding the access opening 11 or a resilient gasket 47 may be attached to the underside of the lid at a recessed portion 48 thereof for engaging the solid metal face 46. In conventional lid structures gaskets have proven unsatisfactory due to the pounding they receive, but in the lid structure of the present invention where vibration and pounding is damped, a gasket may be used advantageously.

40 When the lid structure is in service, the washer 32 and the plate 27 are out of contact with the hood 18 and spring disc 30, as can be clearly seen in Fig. 4, so that no wear can occur due to relative movement of these parts respectively. The lid is imperforate so that it seals the box com-

pletely. The lid is held uniformly against the sides of the face 46 of the box, and more securely than in the case of conventional structures. This is due to the various improved features afore described, which include the universal ball and socket articulation effected by the knob 23, the central pressure of the knob against the spring disc 30 transmitted to the lid close to the inner edges of the box access opening, the shock and vibration-absorbing characteristics of the spring disc 30, and the freedom of movement without freedom for rattling of the parts of the connecting means 20.

When the lid structure is in open position, the spring disc 30 maintains the parts thereof in spring-pressed engagement so that they can not rattle or become misaligned. The tabs 40 prevent unauthorized rotation of the lid relative to the hood about the axis of the rivet 33, and rotations of the lid relative to the hood about transverse and longitudinal crossing axes through the point of contact of the knob 23 and spring disc 30 are limited by the small clearance between the flange 26 surrounding the knob 23 and the adjacent portions of the plate 27. When the lid is swung open, its rotation relative to the hood is limited by engagement of the bottom of the hood with the plate 27. When it is swung closed, the rotation is limited by engagement of the top of the lid with the adjacent portions of the hood side walls. Bending of the lid due to opening and closing stresses, or due to spring closure pressure, is prevented by the strengthening of the lid by the rib 38, the plate 27 and the pocket 35. Bending of the hood at the knob 23 is prevented by the strengthening effect of the knob 23, the flange 26 and the fact that the hood side walls depend to the vicinity of the knob 23.

The spring disc 30 is designed to eliminate the vibration of the lid on the box and reduce wear at all contact points of the lid assembly and box, inasmuch as the inertia forces engendered by the vibrations will act only on the hood and pressure actuating parts of the assembly since the spring disc 30 will flex during vibrations and absorb the energy of the inertia forces so that only a small portion of the total inertia forces acting on the whole box lid assembly will act on the lid 17 and, in this case, the pressure of the spring 19 is more than adequate to keep the lid in full contact with the box face 46.

All the parts adjacent the spring disc 30 are shaped and formed so as to permit full and adequate deflection space for the spring disc 30 when it is undergoing its deflection or vibration in service. The spring disc 30 is of such load-deflection characteristics that there will be little or no change in load during the range of its service movement when it is vibrating, so that there will be little or no change in the pressure that the hood will exert on the lid during such vibrations. The application of the spring closing force at points remote from the actual center of the lid permits the use of lighter weight materials, without sacrifice of strength.

While there has been hereinbefore described an approved embodiment of this invention, it will be understood that many and various changes and modifications in form, arrangement of parts and details of construction thereof may be made without departing from the spirit of the invention and that all such changes and modifications as fall within the scope of the appended claims are contemplated as a part of this invention.

The invention claimed and desired to be secured by Letters Patent is:

1. A journal box structure comprising an open face journal box having a hinge lug and a front wall framing its open face; and a closure structure hinged to said lug, including a lid closing said box, a hood, a pressure spring disposed between said hood and lid for forcing said lid toward said box, a disc disposed between the hood and lid, the disc having a central portion engaging the hood and peripheral portion engaging the lid adjacent the wall, the hood, spring and lug being associated to transmit the closing pressure of said spring to said disc at its center whereby the closing pressure of said spring is transmitted to said lid at portions adjacent said wall, and means loosely securing said hood, disc, and lid together.
2. A journal box structure comprising an open face journal box having a hinge lug and a front wall framing its open face; and a closure structure hinged to said lug, including a lid closing said box, a hood, a pressure spring disposed between said hood and lid for forcing the lower end portion of said hood toward said lid, a spring disc disposed between the hood and lid, the disc having a central portion engaging the hood and a peripheral portion engaging the lid adjacent the wall, the hood, spring, and lug being associated to transmit the closing pressure of the spring to the disc at its center whereby the closing pressure of said spring is transmitted to said lid at portions adjacent said wall, and means loosely securing the hood, disc, and lid together.
3. A journal box structure comprising an open face journal box having a hinge lug and a front wall framing its open face; and a closure structure hinged to said lug, including a lid closing said box, a hood, a pressure spring disposed between said hood and lid, to force the lower end portion of said hood toward said lid, a spring disc disposed centrally of said open face and engaging at its periphery with said lid and at its center with said hood whereby the closing pressure of said spring is transmitted to said lid at portions adjacent said wall and vibrations and shocks emanating in said lid are damped, and means connecting said hood and lid.
4. A journal box structure comprising an open face journal box having a hinge lug and a front wall framing its open face; and a closure structure hinged to said lug, including a lid closing said box, a hood, a pressure spring disposed between said hood and lid, forcing the lower end portion of said hood toward said lid, a spring disc disposed centrally of said open face and mounted under tension to exercise an inward force at its periphery upon said lid adjacent the wall and to exert at its central portion an outward force upon the hood, means connecting said disc at its center with said hood for limited universal movement relative thereto and means loosely securing said hood, disc, and lid together.
5. A journal box structure comprising an open face journal box having a hinge lug and a front wall framing its open face; and a closure structure hinged to said lug, including a lid closing said box, a hood, a pressure spring disposed between said hood and lid, forcing the lower end portion of said hood toward said lid, a spring disc mounted under tension between the hood and the lid so that a constant inward bias is exerted by the disc at its periphery against the lid adjacent the wall and a constant outward bias is exerted by the central portion of the disc against the

hood, means connecting said disc at its center with said hood for limited universal movement relative thereto whereby the closing pressure of said spring is transmitted to said lid at portions adjacent said wall and vibrations and shocks emanating in said lid are damped, and means loosely securing the hood, disc, and lid together.

6. A journal box lid structure comprising a hood provided at its lower end with a ball-type knob; a closure lid provided with an outwardly facing central pocket therein terminating in a plane surface parallel to the outer face of said lid; a pressure spring disposed between said hood and lid; a resilient thrust plate pivoted on said knob by means of a central opening therein for limited universal movement thereon; means secured to said knob for retaining said thrust plate thereon; and a clamping plate disposed on said knob outwardly of said thrust plate and secured to said lid whereby said thrust plate is maintained between said clamping plate and lid with its marginal portion seated on said plane surface for transmitting the force of said pressure spring from said knob to said lid at said plane surface.

7. A journal box lid structure comprising a hood provided at its lower end with a ball-type knob; a closure lid provided with an outwardly facing central pocket therein terminating in a plane surface parallel to the outer face of said lid; a pressure spring disposed between said hood and lid; a spring disc pivoted on said knob by means of a central opening therein for limited universal movement thereon; means secured to said knob for retaining said spring disc thereon; and a clamping plate disposed adjacent said knob outwardly of said spring disc and secured to said lid whereby said spring disc is compressed between said clamping plate and lid with its marginal portion seated on said plane surface for transmitting the force of said pressure spring from said knob to said lid at said plane surface.

8. A journal box lid structure comprising a hood provided at its lower end with a ball-type knob; a closure lid provided with an outwardly facing central pocket therein terminating in a plane surface parallel to the outer face of said lid; a pressure spring disposed between said hood and lid; a spring disc having a central opening therein engaging said knob for limited universal movement thereon; means secured to said knob for retaining said spring disc thereon; and a clamping plate disposed adjacent said knob outwardly of said spring disc and secured to said lid whereby said spring disc is maintained between said clamping plate and lid with its marginal portion seated on said plane surface for transmitting the force of said pressure spring from said knob to said lid at said plane surface.

9. In combination, a journal box, provided with a hinge lug and an access opening; a hood provided with a semi-spherical lower end portion, pivotally connected to said lug; a torsion spring associated with said hood and lug whereby said hood is held in either open or closed position; a centrally apertured spring disc pivoted on the inner convex surface of said semi-spherical end portion for limited universal movement relative to and in the plane of said hood; means loosely restraining said spring disc on said semi-spherical end portion; a closure lid normally closing said access opening, provided with an outwardly facing dished central portion defining an annular surface in the plane of and inwardly of the outer face

of said lid; an annular plate provided with a central clearance opening disposed about said semi-spherical end portion between said hood and said spring disc; and means securing said annular plate centrally to said lid in spaced relation to said semi-spherical end portion whereby said disc is maintained under compression therebetween with its marginal portion seated on said annular plane surface.

10. In combination, a journal box provided with a hinge lug and an access opening; a hood provided at its lower end with a semi-spherical knob, pivotally connected to said lug; a torsion spring co-operatively associated with said hood and lug whereby said hood is held in either open or closed position; a spring disc provided with a central aperture therein partially receiving said semi-spherical knob in "ball and socket" relation; means secured to said knob including a washer loosely restraining said disc for limited universal movement thereon relative to and in the plane of said hood; a clamping ring having a diameter greater than the normal diameter of said disc and diametrically opposite radially extending ears thereon, disposed between said hood and disc in co-axial facing relation; a closure lid for said access opening provided with an outwardly facing central cavity defining a shouldered annular surface in the plane of and inwardly of the outer face thereof disposed in facing relation with said disc with the marginal portion of said disc seated on said annular surface and with said clamping ring disposed on said lid centrally thereof, said annular surface being in close proximity to the defining wall of said access opening; and means securing said ring ears to said lid whereby said disc is initially compressed between said clamping ring and said lid and connected directly to said hood, and said hood is yieldably connected to said lid for transmission of the force of said torsion spring from said hood to said annular surface.

11. A journal box structure comprising a journal box having a cam lug and a front wall defining an access opening; a hood hinged to said lug and having at its lower end a ball-type knob disposed centrally of said opening; a closure lid for said opening seated on said wall and having an outwardly facing central pocket terminating in an annular seat concentric with said knob parallel to the outer face of said lid, and in close proximity to said wall; a pressure spring compressed between said hood and lug; a spring disc universally mounted on said knob with its marginal portion seated on said seat for transmitting the force of said pressure spring from said knob to said lid in close proximity to said wall; and a clamping plate disposed loosely on said knob outwardly of said disc and rigidly secured to said lid, initially compressing said disc between said clamping plate and lid, said disc maintaining said hood and lid in spring-pressed engagement even when open and absorbing shocks and vibrations transferring from said lid to said hood.
